TURN SIGNAL

Walter B. Leifur, Minneapolis, Minn.

Application July 6, 1937, Serial No. 152,009

1 Claim. (Cl. 177—327)

This invention relates to turn signals and more particularly to that type of signal which is adapted for use in connection with vehicles.

It is a general object of my invention to provide a turn signal which is of simple construction and of reasonable cost and which may be quickly and easily applied to a vehicle in a convenient spot so that it will effectively indicate to other persons the intention of the vehicle operator to make a turn or to retard his speed or stop.

It is a further object to provide such a signaling device which may advantageously be operated by a simple and effective electro-mechanical means.

A still further object of the invention is to provide a neat compact structure which will not appear conspicuous when the signal is not in use, but which can be easily seen when the signal is operated.

These and other objects and advantages of the invention will be more fully set forth in the following description made in connection with the accompanying drawing, in which like reference characters refer to similar parts throughout the several views, and, in which—

Fig. 1 is a partial vertical sectional view showing my device mounted in operative position;

Fig. 2 is a transverse section taken approximately on the line 2—2 of Fig. 1;

Fig. 3 is a vertical section taken on the line 3—3 of Fig. 1; and

Fig. 4 is a diagrammatic showing of one form of electrical hook-up.

In the particular embodiment of the invention illustrated in the drawing, I have shown a plate 5 in section, which indicates a portion of the vehicle to which the signal is attached. This may be a portion of the body adjacent the driver's door of a vehicle or it may be any suitable body portion or a supporting bracket placed at any other convenient point on the vehicle. The plate 5 is provided with an aperture adapted to receive a horizontal sleeve 6. This sleeve is secured at its inner end to the plate 5 by means of a nut 7, which will draw the sleeve 6 inwardly until the shoulder 8 abuts the outer surface of the plate 5. The outer end of the sleeve 6 communicates with a generally cylindrical chamber 9, and, as shown in Fig. 2, it is preferred that the sleeve join the chamber 9 in the offset manner illustrated.

The top and bottom of the chamber 9 are preferably open. As shown in Figure 1, the top of the chamber is provided with a horizontally

disposed annular rim 10 and a concentric shoulder portion 11. The upper surface of the rim 10 is adapted to support the under-cut portion of the lower part of the lamp housing 12, and a lip, formed around the edge of the under cut portion of said housing, is adapted to seat upon the shoulder 11. Centrally of the under portion of the lamp-housing 12 is a downwardly extending tubular element 13, which extends to a point adjacent the lower portion of the annular chamber 9. This tube extends through an opening in the center of a retaining disk 14, which seats beneath an inwardly extending shoulder 15, which runs around the inside of the lower portion of the annular chamber 9. A cotter pin 16 extends through the bottom of the tube 13 which is below the disk 14 to retain the entire lamp-housing 12 and its downwardly extending tubular element 13 against up or downward movement, but it will be seen that rotary movement of the lamp-housing is permitted. A suitable cover plate 17 may be provided on the bottom of the chamber 9 to close said chamber in the bottom and cover the lower end of the tube 13.

A vertical cylindrical bore 18 extends upwardly from the tube 13 through the base of the lamp-housing 12 and terminates within the housing in the form of a conventional lamp socket 19 such as is ordinarily used for motor vehicle lamps. The outer shell 20 of the lamp 21 is in contact with and grounded through the lamp housing, and the central contact 22 at the bottom of the lamp bulb is adapted to engage a slideable pin contact 23, which is normally urged upwardly under the influence of a helical spring 24. The lower end of the pin contact 23 is provided with a suitable binding post for the attachment of the end of an electrical conductor 25.

The tube 13 has a lug 26 extending outwardly from the wall thereof and this lug is pivotally connected to a link 27 at one end of the link, and the opposite end of the link is pivotally connected at 28 to a bell crank lever 29, which is in turn pivotally supported on a suitable bracket at 30, which is rigidly mounted upon the plate 5. The opposite side of the bell crank lever 29 is pivotally connected at 31 to the upper end of a link 32, the lower end of the link being pivotally secured to the core 33 of a suitable solenoid 34. The solenoid is supported from the plate 5 by a bracket 35 and said solenoid is electrically connected by wires 36 to the electrical system of the vehicle.

When the solenoid is energized it will draw the core 33 downwardly within the solenoid and

this motion will be transmitted through the link 32, bell crank lever 29 and link 27 to the lug 26 with the result that the sleeve 13 and lamp-housing 12 will be rotated. It is preferred that the movement of the solenoid and the relation of the links and bell crank lever be so arranged that the lamp-housing will be swung through an arc of approximately ninety degrees.

To return the lamp-housing and solenoid to its former position before its actuation under influence of the solenoid, there is provided within the housing 9 a coil spring 37, which has its outer end suitably secured to the inner wall of the housing 9 and its inner end suitably secured to the outer wall of the tubular element 13. Actuation of the solenoid and rotation of the tubular element 13 will cause the coil spring to be contracted or wound and upon the opening of the circuit actuating the solenoid, the tension of the spring 37 will cause reverse movement of the lamp-housing and of the solenoid core 33.

The lamp-housing may be constructed in any suitable manner for properly exhibiting the light from the lamp 21, but it is preferred that the lamp chamber portion of the housing be formed in the relatively long narrow shape illustrated so that the device will blend in with the lines of a present day motor vehicle. As shown, opposite sides of the lamp-housing are provided with openings of relatively long narrow shape and the openings are provided with glass or other transparent or translucent inserts 38, which are preferably colored. These inserts may be held in position by removable flanges 39 secured by screws 40. It is further more desirable to have the lamp socket and lamp positioned in the manner shown so that the outer end of the lamp-housing can swing outwardly to a position which will readily attract the eye of persons in the vicinity of the vehicle.

One form of electrical hook-up is illustrated in Figure 4. As shown, a wire extends from the usual vehicle battery B to the solenoid 34 and another wire from the solenoid to one side of the lamp 21. A suitable circuit breaker 41 is provided to open and close the circuit from the solenoid to the lamp. The other side of the lamp is connected by a wire to the opposite point of

the battery B, or this latter wire may be dispensed with and the completion of the circuit secured by grounding the lamp in the well known one-wire circuit.

From the foregoing it will be seen that I have provided a highly efficient, simply operated and compactly constructed signaling device, which may be readily applied to a vehicle. Since most motor vehicles today have a battery and an electrical system already installed, it is a simple matter to apply my invention to one of these vehicles.

It will, of course, be understood that various changes may be made in the form, details, arrangement and proportion of the various parts without departing from the scope of my invention.

What is claimed is:

A turn signal comprising a supporting bracket including a substantially horizontal tubular portion and an integral substantially circular housing at one end of said tubular portion, said housing being open at its upper and lower ends, a rim around the top of said housing providing a seat, an elongated apertured lamp casing constituting a signalling arm, an end of said lamp casing having a substantially circular downward extension provided with a seat adapted to rotatably rest upon the rim at the top of said housing, an inwardly extending shoulder at the bottom portion of said housing, said lamp casing having a tubular portion extending downwardly into said housing and terminating below said inwardly extending shoulder at the bottom of said housing, a disc-like element resting against the under side of said shoulder within said housing and having a central aperture receiving the lower portion of said downwardly extending portion of said lamp casing, said disc being axially slidable over the end of said downwardly extending casing portion, and a retaining element extending transversely through downwardly extending lamp casing portion and below said disc in close engagement with the underside of said disc to secure the disc on said downwardly extending portion and to anchor said lamp casing against vertical motion.

WALTER B. LEIFUR.
